(57) **CLAIM**

The ornamental design for a cosmetic container with slideable mirror, as shown and described.

DESCRIPTION

FIG. 1 is a top perspective view showing my new design with its cover in a closed position and its slideable mirror in a concealed position;

FIG. 2 is a top perspective view showing my new design with the cover in its open position and the mirror in its exposed position;

FIG. 3 is a top plan view showing the cover in its closed position and the mirror in its concealed position;

FIG. 4 is a front end elevational view showing the cover in its closed position and the mirror in its concealed position;

FIG. 5 is a right side elevational view showing the cover in its closed position and the mirror in its concealed position;

FIG. 6 is a back end elevational view showing the cover in its closed position and the mirror in its concealed position;

FIG. 7 is a left side elevational view showing the cover in its closed position; and,

FIG. 8 is a bottom plan view showing the cover in its closed position and the mirror in its concealed position.

The broken line environmental showing is for illustrative purposes only and forms no part of the claimed design.
